UNITED STATES PATENT OFFICE

2,458,914

SLIDER AND METHOD OF CONSTRUCTING
THE SAMELouis H. Morin, Bronx, N. Y., assignor of one-half
to Davis Marinsky, Bronx, N. Y.

Application July 30, 1943, Serial No. 496,706

15 Claims. (Cl. 24—205.16)

1

This invention relates to the sliders of separable fasteners employed to couple and uncouple the stringers by movement of the slider longitudinally of the stringers. More particularly, the invention relates to a die cast slider structure incorporating an insert, including the frog structure of the slider body, for producing greater strength in the resulting slider in accordance with the method more fully hereinafter described. The novel features of the invention will be best understood from the following description when taken together with the accompanying drawing, in which certain embodiments of the invention are disclosed, and in which the separate parts are designated by suitable reference characters in each of the views; and in which:

Fig. 1 is a longitudinal sectional view through one form of slider, made according to my invention, the section being on the line 1—1 of Fig. 2, but omitting the die parts and cores shown in Fig. 2.

Fig. 2 is a diagrammatic sectional view through dies and cores employed for forming the structure of Fig. 1, the section being substantially on the line 2—2 of Fig. 1, but including the dies and cores around the slider structure.

Fig. 3 is a view similar to Fig. 1, showing another embodiment of the invention; and

Figs. 4, 5 and 6 are perspective views illustrating other types of insert frogs which can be employed.

In the construction of sliders of the kind under consideration, from die cast materials, and particularly when these sliders are fairly large and used upon separable fastener stringers employing relatively large links or scoops, the material employed in the conventional unitary castings, that is to say, sliders where the entire slider structure is formed from the cast material, is not always sufficiently strong to withstand the stresses or strains to which the slider may be subjected.

To overcome these objectionable features, insert frogs can be employed which will be composed of materials stronger than that employed in the cast slider to provide added strength and rigidity thereto. Further these inserts may be extended to include loops or other mounting members for attachment of the finger pieces or pulls commonly employed with sliders of the kind under consideration.

Where inserts are used in conjunction with metallic die cast sliders, the inserts will be composed of metals having greater strength than the material employed in the casting. In other instances, however, and where plastic castings are

employed, the inserts themselves may be formed of die castings as well as of the other stronger metals or materials.

In some instances, certain types of the hard fibrous materials may also be employed as inserts in metallic as well as plastic cast sliders.

In Fig. 1 of the drawing is illustrated one adaptation of the invention in which the slider 10 is formed from spaced die cast members 11 and 12, which basically form the top and bottom plates or walls of the slider body. These walls include at the contracted end portion of the body the conventional inturned flanges 13. At 14 is shown an insert which unites the two bodies 11 and 12, and maintains the same in spaced relationship to each other. The insert comprises a frog portion 15, having recessed ends 16, 17 keyed within the bodies 11 and 12 respectively.

The insert 14 includes at the end 16 an outwardly and longitudinally extending rib 18, which reinforces the wall or body 11, and includes a portion 19 which is countersunk in the body 11. The other end 17 of the insert includes an elongated loop 20, which forms the conventional mounting member for the finger piece or pull. The loop 20 includes a portion 21 imbedded in the body 12. The loop or member 20 also serves as a reinforcing member to reinforce the body or wall portion 12. It will be apparent that where reinforcement of the wall 11 is unnecessary, the rib 18 can be dispensed with, and furthermore, in instances where the loop or other pull mounting is formed integral with the cast slider body, the loop member 20 can also be dispensed with.

In Fig. 3 of the drawing is shown a structure wherein the insert 22 simply comprises the frog portion 23, and the recessed coupling and keying ends 24 and 25 arranged within the spaced wall portions 26 and 27 respectively of the slider body.

In this construction the pull or finger piece loop is formed by a member 28 cast integral with the wall 27.

To illustrate the method of forming die cast sliders with the inserts, I have diagrammatically shown in Fig. 2 of the drawing parts of two dies 29 and 30, and portions of two cores 31 and 32 for forming sliders of the type generally illustrated in Fig. 1 of the drawing. The core 31 has a forked end 33, producing an elongated channel 34 in which a pin or rod end 35 on the core 32 fits. This construction forms within the channel or recess 34 an opening 36 for the reception of the frog portion 15 of the insert 14. Whereas the ends 33 and 35 of the cores 31 and 32 form the space or channels between the walls 11 and 12 of the

resulting slider body, including the inturned flanges 18.

It will be understood that the adjacent surfaces of the dies 29 and 30 will be fashioned to receive the parts 18 and 20 of the insert, and otherwise fashioned to form the general contour of the slider. This includes the extended cast portion 31, which overlies a part of the member 28 where it joins the end 11 of the insert. It will be apparent that with other types of inserts employed, the dies and core members will be correspondingly formed to accommodate the different inserts as well as in modifying the general structure or contour of the slider walls.

In the method of producing castings, it will be understood that the insert 14 is placed between the cores 31 and 32 when in separated position, and when the dies 29 and 30 are in open position. The cores are then closed upon the gate supporting the same firmly within the dies which are then closed, and the casting material is pressure injected through a suitable gate indicated in dotted lines at 38 to form the two die cast bodies or wall structures 11 and 12. Thereupon the dies are opened and the cores separated and the casting removed. This operation is repeated in producing successive castings.

In Fig. 5 of the drawing is shown a modified form of insert which is substantially similar to that shown in Fig. 3, with the exception that instead of having a rectangular cross sectional contour, the insert 39 is of more or less elliptical cross sectional form having a thick rounded end portion 40 and a thinner rounded end 41 which is directed inwardly or in the direction of the contracted end of the slider body when arranged therein. Both ends of the insert 39 are recessed, as seen at 42, to provide the keying of the insert in the spaced walls of the slider body.

Fig. 4 differs from the structure shown in Figs. 3 and 5, in using a round cylindrical insert 43 with recessed ends 44. At this time, it might be well to point out that this type of slider construction lends itself to the formation of frogs of any desired shape and contour, and the inserts may be formed from sheet metal, forgings, or machined parts, and as indicated before, in some instances may constitute individual die castings.

In Fig. 6 of the drawing is shown another simple adaptation of the invention, which would be suitable for the smaller types of sliders, and in this construction the insert 45 is simply composed of a U-shaped body which may constitute a smooth bent wire or a suitably formed wire or strip having a cross head portion 46 to form the frog and extending arms 47 adapted to be arranged along and imbedded in the walls of the slider body in keying the insert in position. It will also be apparent from a consideration of Fig. 1 that inserts of the general type and kind indicated at 45 can be fabricated to include the pull supporting ring or loop similar to the loop member 20.

In the use of inserts of the general type and kind illustrated in Figs. 1 and 6, I not only provide a stronger coupling between spaced walls of the slider body, but the extending arms of the insert also serve to reinforce the wall structure of the slider body.

Having fully described my invention what I claim as new and desire to secure by Letters Patent is:

1. A slider for fastener devices of the kind de-

fined, said slider comprising a die cast body having spaced walls, an insert of denser, tougher material than said cast body, said insert comprising a frog portion centrally located with respect to the longitudinal axis of said walls with keying portions at each end thereof consisting of raised and depressed parts closely embraced by said cast body walls to form said slider.

10 2. A slider for fastener devices of the kind defined, said slider comprising a die cast body having spaced walls, an insert of denser, tougher material than said cast body, said insert comprising a frog portion centrally located with respect to the longitudinal axis of said walls with keying portions at each end thereof consisting of raised and depressed parts closely embraced by said cast body walls to form said slider, one end of the insert including a part protruding beyond the slider wall, and forming a pull supporting member.

15 3. A slider for fastener devices of the kind defined, said slider comprising a die cast body having spaced walls, an insert of denser, tougher material than said cast body, said insert comprising a frog portion centrally located with respect to the longitudinal axis of said walls with keying portions at each end thereof consisting of raised and depressed parts closely embraced by said cast body walls to form said slider, one end of the insert including a part protruding beyond the slider wall, forming a pull supporting member, and part of the cast material of said wall extending onto the protruding portion of said member.

20 35 4. A slider for fastener devices of the kind defined, said slider comprising a die cast body having spaced walls, an insert of denser, tougher material than said cast body, said insert comprising a frog portion centrally located with respect to the longitudinal axis of said walls with keying portions at each end thereof consisting of raised and depressed parts closely embraced by said cast body walls to form said slider, one end of the insert including a part protruding beyond the slider wall, forming a pull supporting member, and the other end of the insert having a member extending longitudinally of the other wall of said slider body.

40 5. In sliders of the class described, comprising die cast body portions, a substantially U-shaped insert forming a cross head with extending arms, the cross head of the insert forming the frog on the slider joining and spacing side walls of the slider body, and said arms extending onto and being embraced by said walls of the slider body.

45 6. In sliders of the class described, comprising die cast body portions, a substantially U-shaped insert forming a cross head with extending arms, the cross head of the insert forming the frog on the slider joining and spacing side walls of the slider body, said arms extending onto and being embraced by said walls of the slider body, and one of said arms forming a loop on one wall of the slider body.

50 7. A slider of the class described, comprising die cast wall portions, a frog joining and spacing said wall portions, said frog constituting an insert around which the wall portions are die cast, and end portions of the insert beyond the limits of the frog having means embraced by said wall portions.

70 8. A slider of the class described, comprising die cast wall portions, a frog joining and spacing said wall portions, said frog constituting an

75

insert around which the wall portions extend, end portions of the insert beyond the limits of the frog having means embraced by said wall portions, and the last named means forming a pull loop.

9. A slider of the class described, comprising die cast wall portions, a frog joining and spacing said wall portions, said frog constituting an insert around which the wall portions extend, end portions of the insert beyond the limits of the frog having means embraced by said wall portions, and said last named means extending longitudinally of said wall portions to reinforce the same.

10. In sliders of the class described, a frog having terminal end portions, an encircling groove in each said end portion, and a die cast plate portion embracing each end portion including said groove, said plate portions being united and spaced by said frog.

11. A slider of the class described, comprising spaced wall portions of a die cast material, an insert of another material stronger than that of said wall portions joining and spacing said wall portions, said insert forming the frog of the resulting slider, said wall portions surrounding said insert, and means on the ends of the insert embraced by the wall portions to retain the wall portions against relative movement to each other and to said insert.

12. The method of producing a die-cast slider with a frog insert, which comprises forming said insert with suitable raised and depressed keying end portions adapted to be embraced by the walls of said slider, supporting said insert between relatively movable core members arranged upon the parting line of relatively movable dies, pressure injecting casting material into the cavity of the dies and around the core members and insert to form the cast slider body comprising spaced walls arranged on said keying end portions of the insert and spaced apart thereby, and finally separating the dies and core members to remove the slider therefrom.

13. The method of producing a die-cast slider with a frog insert, which comprises forging said insert with suitable raised and depressed keying end portions adapted to be embraced by the walls of said slider, supporting said insert between relatively movable core members arranged upon the parting line of relatively movable dies, pressure injecting casting material into the cavity of the dies and around the core members and insert to form the cast slider body comprising spaced walls arranged on said keying end portions of the insert and spaced apart thereby, and finally separating the dies and core members to remove the slider therefrom.

14. The method of producing a die-cast slider with a frog insert, which comprises forging and machining said insert with suitable raised and depressed keying end portions adapted to be embraced by the walls of said slider, supporting said insert between relatively movable core members arranged upon the parting line of relatively movable dies, pressure injecting casting material into the cavity of the dies and around the core members and insert to form the cast slider body comprising spaced walls arranged on said keying end portions of the insert and spaced apart thereby, and finally separating the dies and core members to remove the slider therefrom.

15. The method of producing a die-cast slider with a frog insert, which comprises machining said insert with suitable raised and depressed keying end portions adapted to be embraced by the walls of said slider, supporting said insert between relatively movable core members arranged upon the parting line of relatively movable dies, pressure injecting casting material into the cavity of the dies and around the core members and insert to form the cast slider body comprising spaced walls arranged on said keying end portions of the insert and spaced apart thereby, and finally separating the dies and core members to remove the slider therefrom.
